UNITED STATES PATENT OFFICE.

DWIGHT S. RICHARDSON, OF NEW YORK, N. Y.

SECTIONAL BOILER.

SPECIFICATION forming part of Letters Patent No. 761,252, dated May 31, 1904.
Application filed March 22, 1904. Serial No. 199,389. (No model.)

To all whom it may concern:

Be it known that I, DWIGHT S. RICHARDSON, residing at New York city, in the county of New York and State of New York, have invented certain new and useful Improvements in Sectional Boilers; and I do hereby declare the following to be a full, clear, and exact description of the same, reference being had to the accompanying drawings, forming a part 10 of this specification, and to the letters of reference marked thereon.

The present invention relates to improvements in boilers or water-heaters, more especially of that type adapted for heating purposes or where a high boiler-pressure is not desired.

The objects of the invention are to provide a sectional boiler the sections of which may be multiplied or reduced to form a boiler of greater or less capacity and so constructed as to provide for a maximum surface exposed to the fire with a minimum flue-surface.

Other objects of the invention are to provide a boiler of ample capacity and heating-surface, but comparatively narrow from front to rear of the fire-pot in order to facilitate stoking and removal of ashes and also to provide for the complete and effective draining of the sections, as well as for the convenient and effective cleaning of the sections and flues.

In the accompanying drawings, Figure 1 is a perspective view showing two end and one intermediate sections of a boiler assembled on a suitable base or ash-pit section, portions of the walls being broken away to disclose the parts which would be concealed thereby. Fig. 2 is a side elevation of one of the intermediate sections. Fig. 3 is an elevation of one end of the upper portion of the boiler with a portion of the clean-out doors broken away. Fig. 4 is a similar view looking at the opposite end of the boiler.

Like letters of reference in the several figures indicate the same parts.

In said drawings the letter A, Fig. 1, indicates a base or ash-pit section of the boiler-furnace and may be of any approved type of construction. It is preferably, however, provided with doors A' at the front for the re-

moval of ashes and damper-doors A'' at the sides. In this type of boiler the sections which constitute the boiler proper and inclose and form the fire-pot are mounted on the base-section K and consist, preferably, of two end sections B B' and a number of intermediate sections C, the number of the latter determining the size and capacity of the boiler. It is obvious that a greater or less number of said intermediate sections may be employed, and consequently castings will be uniform for all of the different sizes of boilers which it may be desired to market. The boiler illustrated in Fig. 1 is an eight-section boiler, five of the sections being omitted in order that the construction and arrangement of the sections may be more clearly shown.

Each of the intermediate sections C is formed with a water-leg C' at the rear adapted to rest on the base-section and collectively form the rear of the fire-pot. The upper portions of these intermediate sections extend forward over the fire-pot and preferably take a bearing or rest on a front section D, which may be a water-front of ordinary construction, but is in every instance provided with the stoking or fuel doors D', the sections thus being arranged to extend from front to rear of the furnace or at right angles to the doors and permitting of the formation of a furnace narrow from front to rear, thereby greatly facilitating stoking and removal of ashes.

The overhanging portions of the sections, as will be seen from Fig. 2, will drain into the water-leg at the rear, but are provided with a series of transverse openings c and intermediate circulating-ducts c', connecting the top and bottom portions, and at the rear each section is provided with a transverse opening C', which when the sections are assembled constitutes the transverse smoke-flue, as will be presently explained.

The water-legs and peripheral back, top, and front portions of the sections are made of sufficient thickness to abut or lie close together when the sections are assembled, while the overhanging or intermediate portions are sufficiently reduced in thickness to permit the products of combustion to circulate up be-

2
tween them and to pass transversely through the passages c , which latter thus constitute a portion of the combustion-chamber, and inasmuch as the surface area of these portions of the sections is greatly in excess of the other portions the boiler will have a very large fire-surface in proportion to the size of the boiler and will have all of the advantages of a drop-tube boiler, but with the additional advantages of perfect drainage and circulation throughout.

The end sections B B' are preferably formed similar to the intermediate sections, save that they have no overhang, and the bottom portions constitute the side walls of the fire-pot, as shown at D^2 in Fig. 1.

The edges of the flue-openings C^2 are flanged, as at c^2 , so as to fit tightly together, and suitable water-circulating openings c^3 are formed in the sections at appropriate points, top and bottom, for the flow of water and steam from section to section.

The products of combustion pass up between the sections and off toward one end, as indicated by the arrows, Fig. 1, said products returning to the opposite end of the boiler through the smoke-flue formed by the openings C in the several sections and thence to the stack, and the arrangement is preferably such that the stack or discharge-flue may be located at either end of the boiler, as found most convenient for any particular situation.

Various ways of forming the communication between the combustion-chamber and smoke-flue at one end and between the smoke-flue and stack at the opposite end of the furnace will suggest themselves when the manner of assembling the sections is understood, and in the accompanying drawings the preferred means for accomplishing these ends is illustrated. The preferred means consist of smoke-boxes located at each end of the boiler. Thus a smoke-box F is located at one end of the boiler outside of the end section B' to form a passage through which the products may pass from the passages c to the smoke-flue C^2 , as shown clearly in Fig. 3, and this smoke-box is preferably provided with large clean-out doors F' , which will give free access both to the smoke-flue and to the passages c from one end to the other of the boiler. At the opposite end a smoke-box G is provided for conducting the products from the smoke-flue C^2 to the stack-opening g , a diaphragm or deflector G' being preferably provided in this box to deflect the products downwardly in passing through the box. The bottom of the box is provided with a clean-out door G^2 and a direct damper H . By opening the latter the products may pass directly from the combustion-chamber and passages c through the box G to the stack instead of passing indirectly thereto, as before explained.

Obviously the smoke-boxes may be made

to fit either end of the furnace, and thus with a furnace of the same construction it may be set to have either a right or left hand discharge.

Having thus described my invention, what I claim as new, and desire to secure by Letters Patent, is—

1. In a sectional boiler wherein the sections extend from front to rear, the combination of the end sections, the intermediate sections each having an overhanging forwardly-extending portion between which the products of combustion pass and transverse openings in said overhanging portions for the passage of products toward the ends of the furnace, said sections also having registering openings forming a return smoke-flue, a duct for the passage of products from the combustion-chamber to one end of said flue and from the opposite end of said flue to the stack; substantially as described. 85

2. In a sectional boiler wherein the sections are arranged side by side and extending from front to rear, the combination of the end sections, the intermediate sections each having a downwardly-extending water-leg at the back and an overhanging forwardly-extending portion with transverse passages therein, said overhanging portions being thin throughout a portion of their area to permit products to pass between the sections and having registering openings in rear of said overhanging portions to form a smoke-flue, a duct at one end of the furnace to carry the products into the smoke-flue and a duct at the other end of the furnace to carry the products from the smoke-flue to the stack; substantially as described. 95

3. In a boiler, the combination with the end sections having transverse openings therein, of the intermediate sections having the relatively thin overhanging portions located in the combustion-chamber and having transverse openings therein for the passage of products toward the ends of the furnace, said sections having registering openings at the rear forming a return smoke-flue and smoke-boxes outside of the end sections for conducting the products to and from said smoke-flue; substantially as described. 105

4. In a boiler, the combination with the end sections having transverse openings therein, the intermediate sections having the depending water-legs and abutting peripheral portions at rear top and front and central portions spaced apart to permit products to pass between them, said central portions being provided with transverse openings to permit the products to pass toward the ends of the furnace, said sections also having registering openings forming a smoke-flue extending from end to end of the furnace, of smoke-boxes at the ends of the furnace, one forming a duct to carry the products into the smoke-flue, the 110 120 125

other forming a duct to carry the products to the stack and a direct-draft damper located in the latter and operating to close the transverse openings in the central port of the end section; 5 substantially as described.

5. In a boiler, the combination of a series of sections arranged side by side and forming a combustion - chamber, overhanging portions on the intermediate sections projecting into the combustion-chamber, said sections having transverse registering openings in rear of the combustion-chamber forming a transverse smoke-flue entirely within the sections, ducts for carrying the products from the combustion-chamber into one end of said smoke-flue and from the opposite end of said flue to the stack; substantially as described.

6. In a boiler, the combination of a series of sections extending from front to rear and arranged side by side to form a combustion-chamber, the intermediate sections having overhanging portions projecting into the combustion-chamber with transverse openings in said overhanging portions, the sections also 25 having transverse registering openings in rear of the combustion-chamber forming a transverse smoke-flue entirely within the sections, a duct at one end for carrying the products from the combustion - chamber to the said smoke-flue and a smoke-box on the outside of the boiler at the opposite end of said flue for conducting the products from the flue to the stack; substantially as described.

7. In a boiler, the combination of a series of

sections extending from front to rear and arranged side by side to form a combustion-chamber, the intermediate sections having overhanging portions projecting into the combustion-chamber with transverse openings in said overhanging portions, the sections also 35 having transverse registering openings in rear of the combustion-chamber forming a transverse smoke-flue entirely within the sections, a duct at one end for carrying the products from the combustion - chamber to the said smoke-flue, a smoke-box at the opposite end of the furnace into which the flue opens, an exit-opening in said box and a direct damper between the combustion-chamber and smoke-box; substantially as described.

8. In a boiler, the combination of a series of sections arranged side by side to form a combustion - chamber, the intermediate sections having relatively thin portions projecting into the combustion-chamber with transverse openings in said thin portions and registering transverse openings in the sections in rear of the thin portions to form an unbroken smoke-flue 55 from side to side of the sections, of smoke-boxes at each end of the boiler for conducting 60 the products to and from the smoke-flue and a clean-out door in line with the transverse openings in the sections; substantially as described.
